UNITED STATES PATENT OFFICE.

GEORGE W. BELLIS, OF GALION, OHIO, ASSIGNOR TO THE NATIONAL GRAVE VAULT COMPANY, OF GALION, OHIO.

CASKET-CARRIAGE FOR BURIAL-VAULTS.

1,194,810.

Specification of Letters Patent. Patented Aug. 15, 1916.

Application filed March 13, 1915. Serial No. 14,273.

To all whom it may concern:

Be it known that I, GEORGE W. BELLIS, a citizen of the United States, residing at Galion, in the county of Crawford and State 5 of Ohio, have invented certain new and useful Improvements in Casket-Carriages for Burial-Vaults, of which the following is a specification.

This invention relates to casket carriages 10 for burial vaults, and has as its object to provide a carriage which will be inconspicuous, and upon which one end of the casket may be readily disposed when the casket is to be placed within the vault.

15 The carriage embodying the present invention is designed more particularly for use in metallic burial vaults, and thus the primary aim of the invention is to so construct the carriage that it will firmly support the end of the casket spaced from the floor of the vault as the casket is introduced into the vault, so that as a result the introduction of the casket is not accompanied by the usual grating noise, and it is not liable 20 to meet with obstacles, rendering it unnecessary to shift it about as it is slid into place.

A further object of the invention is to provide for the proper guidance of the carriage as it travels toward the closed end of 30 the vault, and to so construct the carriage that it will not be liable to slip or tilt from beneath the end of the casket.

For a full understanding of the invention, reference is to be had to the following description and accompanying drawings, in which:—

Figure 1° is a vertical longitudinal sectional view through a vault, illustrating the carriage embodying the present invention, 40 and the track upon which the carriage travels, the view illustrating also one end of the casket supported upon the carriage; Fig. 2 is a perspective view looking at the underside of the carriage removed from the vault; 45 and Fig. 3 is a vertical transverse sectional view through the carriage and floor of the vault and the track for the carriage.

Corresponding and like parts are referred to in the following description, and illustrated in all the views of the accompanying drawings by the same reference characters.

In the drawings, the body of the vault is indicated by the numeral 1 and the bottom or floor thereof by the numeral 2. The 55 vault is provided, as usual, with a closed

end 3 and an open end 4, which is to be closed by means of a door (not shown) seating against a flange 5 secured upon the inner side of the walls of the vault. This flange 5 constitutes an element of a locking 60 means for the door, which, however, is neither shown nor described for the reason that it constitutes no part of the present invention. The flange, however, as ordinarily proportioned is adapted to perform a 65 function aside from its function in the locking device, as will be presently explained.

The carriage embodying the present invention is to travel upon a track which is secured upon the floor of the vault, and 70 which as shown in Fig. 3 of the drawings is of channel-iron formation, the channel or groove of the track being indicated by the numeral 6 and its attaching wings by the numeral 7.

75 The carriage embodying the present invention consists essentially of a plate 8, which is in general outline preferably rectangular, although it may assume some other form if found desirable. At the forward end of the carriage, the plate 8 is bent to form an upwardly projecting abutment flange 9 against which may be disposed the end of the casket supported by the carriage. A bearing bracket 10 is mounted upon the 80 under side of the plate 8 immediately adjacent the upturned forward end 9 thereof, and in this bracket is journaled a roller 11 of a width to be received within the channel or groove 6 of the track. At this point it 85 will be understood that the roller is to travel in the groove of the track, and that it supports the carriage 8.

By reference to Fig. 1, it will be observed that the flange 5 is of such height at its 90 portion which extends across the floor 2 of the vault that the rear end portion of the plate which comprises the body of the carriage may rest upon its upper edge, the forward end of the plate being supported 95 by the roller 11. When so arranged, the end of a casket may be readily placed upon the carriage in position abutting against the upturned forward end 9 thereof, after which the other end of the casket may be slightly 100 lifted and the casket shoved into the vault. Due to the forward pressure exerted by the end of the casket against the portion 9 of the carriage, there will be a tendency for 105 the rear end of the carriage to tilt upwardly 110

and, consequently, it is necessary to employ but a single roller for supporting the carriage. It will furthermore be understood that the carriage is guided in its travel within the vault although supported by a single roller, for the reason that the roller is guided by the channel in the track. It will also be noted that due to the engagement of the end of the casket against the forward end 9 of the carriage, there will be little or no likelihood of the carriage tilting from beneath the casket, or of the casket slipping off from the carriage.

What is claimed is:—

15 The combination with a receptacle having a door opening therein and provided upon its bottom inwardly of the door opening

with a flange, of a track arranged upon the said bottom of the receptacle and extending inwardly from the flange, and a carriage including a supporting body, and a roller supporting said body and located forwardly of the transverse middle of the carriage and resting upon the said track, the roller supporting the forward end of the carriage, and the said flange being adapted for the support of the rear end of the carriage.

In testimony whereof I affix my signature in presence of two witnesses.

GEORGE W. BELLIS. [L.S.]
